VENDING MACHINE

Original application filed October 26, 1925, Serial No. 64,735. Divided and this application filed April 6, 1931. Serial No. 528,024.

This application is a division of my application filed October 26, 1925, Serial No. 64,735.

An object of this invention is to provide a device in which stacks or tiers of receptacles are lodged to be singly delivered from time to time as required.

Another object is to provide an improved mechanism whereby a single cup will be delivered to an operator who has set a cup vending mechanism in motion.

A feature of the invention lies in the novel arrangement of gear operated cams, so that a single cup will be separated from its stacked companions and delivered to the operator.

Another feature of my invention lies in the novel use of cams to support a stack of nested cups in a magazine.

Still another feature of invention lies in the means used to act upon and enter between the rims of the stacked cups so that the lower cup of the series is wedged apart and separated from the remainder of the cups.

Advantages of my invention are, relative simplicity of construction, certainty of operation, undamaged merchandise and sanitation.

The accompanying drawings illustrate the invention in form at present deemed most desirable.

Figure 1 is a broken front elevation of a dispensing machine constructed in accordance with this invention with a filled cup ready for delivery and the crank returned to position for starting another operation. Broken lines indicate the position of the crank at the coin dislodging instant.

Fig. 2 is a plan of one of the three cup-feeding disks.

Fig. 3 is an elevation of the rear cup-feeding disk.

Fig. 4 is an elevation of one of the front cup-feeding disks.

Fig. 5 is a broken side elevation of the machine looking from the left in Fig. 1 and showing a fragment of the case. A portion of one side wall of the frame is broken to expose the cup passage; broken lines indicate mechanism outside the other wall.

Fig. 6 is a side elevation looking from the right in Fig. 1.

Fig. 6a is a fragmental elevation of the cylinder head showing the pressure liquid inlet valve and the means for operating said valve.

Fig. 7 is a sectional view taken on the irregular line $\alpha 7-\alpha 7$, Figs. 1, and 8 omitting the pressure liquid pipe and other parts.

Fig. 8 is a plan view of the machine with most of the parts in the position shown in Figs. 1, 5, 6 and 7, omitting the filled cup shown in Fig. 1.

Fig. 9 is a fragmentary sectional view of the cup dispenser with cups in place, viewed from line $\alpha 9$, Fig. 10.

Fig. 10 is a plan view of the cup dispenser.

Fig. 11 is an elevation showing the left side of the cup dispenser shown in Fig. 10.

Fig. 12 is a view looking up at the bottom of the cup dispenser mechanism shown in Figs. 10 and 11.

Fig. 13 is a fragmentary vertical section on line $\alpha 13$, Fig. 14. Broken lines indicate the position of parts the moment before the knockout tappet is sprung to eject the coin from the coin carrier.

Fig. 14 is a fragmentary vertical section on lines $\alpha 14-\alpha 14$, Figs. 1 and 13.

Fig. 15 is a fragmentary right side elevation of the forward end of the machine; parts are broken away to show interior construction.

Fig. 16 is a fragmentary rear elevation of the forward end of the machine, looking from the right side of Fig. 15, and from a plane indicated by line $\alpha 16$ in Fig. 7.

Other objects, advantages and features of invention may appear from the accompanying drawings, the subjoined detail description and the appended claims.

It will be obvious that the cup dispensing means is per se an invention and may be operated, if desired, separately from any drink dispensing means or coin controlled mechanism. For such latter operation it is only necessary to make the shaft 15 continuous between the handle 7 and gear 17, in other words, to eliminate the gap intended to be bridged by the coin. A cup will then be dis-

pensed at each turn of the handle and no coin need be inserted, in fact no coin slot is then necessary. If the coin controlled parts are eliminated the cup vending device may be operated either with or without the liquid dispensing device attached thereto.

Hence the cup vending mechanism which is hereinafter described and claimed may be combined with many different kinds of dispensing machines constructed to dispense liquids or other substances adapted to be delivered in cups or like receptacles, whether or not such machines are of the vending type or of the coin-controlled type. In the drawings of the present application a coin-controlled drink vending mechanism is illustrated designed to vend a drink consisting of two component parts; viz., a syrup and a charge of carbonated water delivered under pressure and mixed with said syrup by the machine at the time of its delivery therefrom.

It is intended that in common use the machine *a* will preferably be housed in a cabinet *K*, a fragment of which shown in Fig. 5, and that only part of the front of the machine will be exposed to view, while the remainder of the machine is covered by the cabinet to prevent tampering with or injury to the machine proper.

The cast metal frame of the machine is shown as comprising base and top members 1 and 2 connected by struts 3 at either side, spaced apart and secured to said base and top by cap screws 3a and 3b.

The base casting 1 is provided with a recess 4, which is open at the front side and has a horizontal U-shaped forwardly open lip 4a upon which the vended cup 5 is received from the nested cups in the magazine 28 in which the receptacles to be vended are supported prior to delivery of the cup and reception of a drink therein.

A spout 5' takes care of the drip, and a chute 5'' to receive the used cups leads from the frame 1 to a suitable receptacle not shown.

The casting 1 is also formed with a vertical passage 6 opening down to the recess 4, and through which the cups are delivered one at a time from a magazine to the lip 4a, by cup dispensing means, when the machine is operated.

The manually operated actuating mechanism comprises a hand crank 7 fixed to a horizontal shaft 8 that is journalled in a rib 1a at one side of the base casting 1 and projects from the rear face thereof, and that is there and provided with a coin carrier 9, rigidly fixed to the crank shaft 8 by a pin 8' and to a bearing 10 that extends to a rib 11 of the frame. (See Figs. 6 and 14.)

12 is a coin slot open to the front of the frame and is of sufficient cross section to receive and conduct a coin of the denomination

required to pay for one of the cups to be vended.

The coin carrier 9 is preferably U-shaped and the open space 9' between the limbs of the U is of less width than the coin slot 12.

In the inside faces of the limbs of the U, grooves 12' are cut to continue the coin slot downward, and these grooves are adapted at their lower ends to unitedly form a coin seat 9a to seat a coin 13 to bridge the open space between the limbs of the U to bear against and operate a lug 14 and retract a tappet 14' when the crank 7 is turned for the purpose of operating the vending mechanism.

The lug 14 and tappet 14' are fixed to, and extend on opposite sides of, a transmitting shaft 15 that is journalled in both limbs of the carrier 9, and also in the bearing 10 and in the rib 11.

A coil spring S is coiled upon the bearing sleeve 10 and is arranged to yieldingly hold the coin carrier against the outside of the frame member 1 in position to receive from the coin slot 12 a coin 13 to bridge the space 9' and to key the coin carrier 9 to the lug 14 to turn the shaft 15, to which the lug 14 is fixed by pin 15'. (See Fig. 15.)

Said slot 12 is formed in the frame member 1, and extends from the front face of said member to deliver a coin 13 into the coin seat 9a (see Fig. 14) in the coin carrier when said carrier and other parts of the machine are in coin receiving position.

When there is no coin in the coin seat 9a the crank 7 may be oscillated almost throughout one revolution and the carrier stops against the frame at each end of its arc of travel.

The spring S returns the carrier with considerable force to its stop on the outside of the frame, and there is likely to be more or less battering of the frame or the carrier, thus misaligning the seat with reference to the slot, and to correct this difficulty, adjustable stop lugs 16 in the form of screws are threaded through the carrier to engage the frame so that when the contacting surfaces become battered the coin seat may be again alined with the slot by screwing the stops further through the carrier, thus causing the carrier to stop in position to receive the coin from the coin slot. (See Figs. 8 and 9.)

When the coin slot 12 is unobstructed and a coin of required size is dropped thereinto such coin passes down into the coin seat 9a and then upon oscillation of the crank, the coin engages and causes the lug 14 to swing around, thus transmitting motion to the shaft 15, thereby revolving a bevel gear 17 which is fixed on the inner end of the shaft 15.

The bevel gear 17 meshes with a gear 18 fixed to a vertical shaft 19, which is journalled at the rear of the base member 1 in ears 20, projecting from said member, and

is connected to operate the cup delivering mechanism detailed in Figs. 12, 13, 14, 15 and 16.

5 A gear 21, (see Figs. 5 and 6) meshes with the gear 18 and is fixed to one section 22 of a horizontal shaft which is formed of two torsionally connected sections 22 and 22'. A revolvable member in the form of a cam wheel 23 is fixed to the section 22' and is arranged 10 and connected to complete the operation of the cup delivering mechanism.

The lug and tappet 14 and 14', vertical shaft 19, the cup delivering means, and the cam wheel 23 are thus connected for coordinate operation.

15 A master spring preferably formed of two coils 27, eccentrically connected by crank pin 27' to the revolvable cam wheel holds said cam wheel normally in a predetermined position, and the operation of the lug 14 by the coin is against the resistance of said master spring and such resistance affords a friction on the coin that tends to hold the coin in the coin seat while operating the lug. The coin enters 20 the coin seat from above, and when the coin carrier is revolved sufficiently to invert the coin seat, the coin would drop out if it were not for the friction caused by the resistance of spring 27, which is given tension by the 25 initial rotational movement of the cam 23; and when the cam crank pin 27', by which the master spring 27 is eccentrically connected to the cam 23, comes to dead-center as the spring swings across the axis of the cam, the 30 resistance of the master spring to the advance of the lug under the pressure of the coin carried by the coin carrier is so reduced that the friction on the coin would be insufficient to uphold the coin, and the coin would drop 35 out of the inverted coin carrier, thus leaving no connection between the coin carrier and the cam 23, so that the operation of the machine would not be carried on.

To overcome this difficulty, the cam operating shaft is made in the two alined sections 22 and 22' and these sections are connected to each other by a torsion coupling comprising an intermediate spring 22a the ends of which are fixed to the sections 22, 22', 40 respectively, by means of sleeves 22b and 22c.

45 Said intermediate spring 22a is of such strength that when it is put under tension by the resistance of spring 27, as it approaches the dead center position, the reaction of said spring 22a against the lug is sufficient not only to frictionally hold the coin until the dead center position is reached, but also to suddenly thrust the cam wheel 50 onward after spring 27 passes the dead center; and the moment this occurs spring 27 operates to instantly turn the cam 23 to normal or initial position where it comes to rest and is held in such initial position by the 55 tension of the spring 27.

60 The intermediate spring 22a is so adjusted

by means of screw *d* in the collar *e* on the coupling sleeve 22b which is fixed by pin *f* to the shaft member 22 that the tension of spring 22a will be sufficient to accomplish the results above set forth. The cam 23 when returned to normal position also returns the gears 21, 18 and 17 to a pre-determined normal position and the lug 14, being fixed to shaft 15 which is fixed to gear 17, will be positioned so that lug 14 will be just in front of the coin seat 9a in order that a coin may be easily received in said seat.

75 When the spring 27 passes the dead center and spring 22a returns to normal position, the lug 14 is withdrawn from the coin so that the coin is free to drop by gravity from the coin seat 9a. Further movement of the cam 23 by spring 27 revolves shaft 15 and moves the tappet 14' against the coin to positively kick the released coin out of the coin seat in the event the coin has not previously fallen therefrom by gravity.

80 The shaft member 22 is journalled at one end in a block 24, and the other member 22' is journalled in a casting 25 depending from a casting 26 secured to the bottom of the casting 2. (See Figs. 5 and 6).

85 The spring 27 secured to the eccentric cam pin 27' on the cam wheel 23 and to the frame, yieldingly holds the said wheel 23 and its connections at the rest position, and it not only operates the tappet to eject the coin, but also operates means to dispense cups.

90 The crank is only oscillatable and stops short of a complete revolution, as indicated in Fig. 1, and the gears 17, 18, 21 are so arranged that the cam wheel 23 can be turned to a point somewhat more than 180 degrees from rest by operation of said crank and before the crank reaches the limit of its movement the cam wheel and the tappet are automatically caused by reaction of spring 27 to complete a full revolution on and to return to rest to complete the cup vending cycle of operation.

95 Said spring 27 is arranged in two upwardly diverging sections or limbs, one of said sections being secured at its upper end to the fastening element 27x and the other of said sections being secured at its upper end to the fastening element 27z. The fastening element 27x is on one side of a perpendicular plane drawn along the axis of rotation of the cam 23, and the fastening element 27z is located on the other side of said plane, said fastening elements being far enough apart to stabilize the action of the spring sections 27 upon the pin 27' of the cam 23, thus yieldingly but positively normally maintaining said cam at rest in the position shown in Fig. 5, and automatically restoring such cam to said position of rest after the shaft upon which it is mounted has made a 100 complete rotation and the cycle of opera- 105

110

115

120

125

130

tions which accompanies the vending of a cup has been completed.

The cup dispensing device comprises a magazine 28 mounted on and stationary to the casting 1 and has a circular cup-way 29 above and axially aligned with the passage 6, and having a chamfered internal flange 30 below which thin mutilated worm-rimmed or peripherally threaded revoluble cup feeding disks 31, are arranged to support a stack of nested cups C in the magazine. Said disks are mounted on shafts 32 and 32' and are arranged to be revolved relative to the magazine. They are arranged with their spiral peripheries projecting into the cup-way 29

10 to unitedly support the rim flange of the lowermost cup at one part of the revolution and the spiral peripheral grooves in said disks are adapted to receive the rim flange of the lowermost cup and move such rim down and thus cause the cup to drop into the vertical passage 6 when the disks are turned to the appropriate position for supporting the next cup rim.

15 Preferably there are three of such disks symmetrically disposed, as shown, and in fixed relation to respective operating gears.

20 A gear 33 and its disk 31 are in fixed relation to shaft 32, and the gear 33 meshes with an annular gear 34, which is journalled on a depending collar 35 on the flange 30 and is initially revolved by power applied through the hand crank 7. Disk gears 36 and 37 are fixed to the other disks 31, and mesh with the ring or annular gear 34 to be revolved thereby; so that all three disks revolve alike when the shaft 32 is revolved.

25 As shown in Figs. 9 and 12, the cups C have flanged rims b and are nested one within another in the chamfered flange 30, with the flange b of the bottom cup resting on the disks 31. As these disks rotate, their threaded peripheries receive and engage the flange b of the bottom cup and move it down until the cup drops through the passage and rests on the lip 4a in the recess 4.

30 The rotation of the disks 31 is effected through a train of gears comprising gear 39 fixed to shaft 19, and meshed with gear 40 that is fixed to shaft 41, to which is fixed gear 42 that is meshed with gear 43, fixed to shaft 32 which turns gear 33 that revolves annular gear 34, by which the disk gears 36 and 37 are revolved. When the crank is turned, 35 with coin in place, the shafts 19 and 41 will be turned, and also the gear 43 and thus revolve the annular gear 34, and the disks 31 will be simultaneously rotated to dispense a cup. The cam wheel 23 on shaft member 22' 40 is turned through an arc to stretch the spring 27 which instantly completes the revolution of the shaft 22, when the spring passes dead center.

35 Owing to the manner in which the springs 27 and 22a cooperate to give a sudden for-

ward impulse to the cycle of movements which accompany a complete operation of the crank 7, the three threaded gears which propel the cups C downwardly are simultaneously quickly rotated during the latter part of each cup-delivery movement, thus safeguarding the cups from sticking and causing them to be quickly and positively thrown down upon the lip 4a in the recess 4.

40 A counter 44 (see Fig. 1) is operatively connected to one of the shafts 32' and records the number of cups dispensed by the machine, and therefore the number of times it is operated.

45 Means are provided to prevent the insertion of a coin when the supply of cups is exhausted, and such means comprise a spring actuated coin stop operating arm 45 (see Fig. 8) that is pivoted intermediate its ends at 45° and is provided at one end with finger 46 50 constructed and arranged to be pressed against the rim of a disk supported cup by a spring 45 which may, as shown in Fig. 8, constitute the terminal portion of a spring 47. Said spring 47 tends to insert a stop 48 55 mounted at the other end of arm 45 into the coin slot 12 at a point close to the front of the frame so that when the stop is in the hole it will prevent the insertion of a coin too far into the slot to be withdrawn by the operator.

60 In this way when the last cup is dispensed from the stock so that it is removed from the part 46 of the device, the spring 47 acts to move arm 45 to insert the stop 48 and prevent loss of a coin by an intending customer.

65 The friction of the finger 46 on the rims of the cups would prevent the cups from moving down, and it is necessary to withdraw the finger from the cups during the operation of dispensing a cup, and this is effected by a pin 49 normally retracted by a spring 50 and adapted to be inserted into slot 12 through a hole, and into engagement with the stop 48 to push said stop back to oscillate arm 45 and retract the finger 46 from the cup; a lever 51 (see Fig. 15) fulcrumed to frame at 52 has a finger 53 operable by a cam 54 fixed to the crank-shaft 8, to push the pin 49 into the position for retracting said finger 46 after a coin has been dropped into the coin carrier, and directly after the crank 7 has been moved to turn the coin carrier and the cup dispensing device. When the pin 49 has been moved into engagement with the stop 48 it has passed transversely through the coin slot 12 so that another coin cannot be inserted in said slot and also provides a means for requiring the handle 7 to be in initial position when a coin is inserted and thereby assures correct positioning of the coin carrier relative to the slot 12 when the coin is inserted.

70 The cam 54 extends around the axis of the shaft 8 sufficiently to hold the lever 51 and pin 49 in finger retracting position through-

out all except a limited initial arc of the crank oscillation, so that while the cup feeding disks 31 are lowering the cup, the finger 46 is held retracted from the path of the projecting cup rim, but when the crank is returned to its initial position shown in solid lines in Figs. 1 and 14, the spring 47 again presses the finger 46 against a cup, and the stop 48 is withdrawn from the coin slot so long as cups are in the cup receptacle, and when the cam 54 is withdrawn from the lever 51, the spring 50 withdraws the pin 49 from the coin slot 12 leaving said slot free for the insertion of another coin.

15 The drink dispensing mechanism is contained and supported by a hollow casting 55 having a cover plate 56.

16 A fountain tray 57 is provided and a fountain or jar 58 is inverted thereon. A tube 59 leads from the tray 57, being secured to the casting by screws threaded into flanges 60. Said tube opens into an intake chamber 61, which in turn, opens into a measuring or pump cylinder chamber 62. Said chamber 62 communicates with outlet chamber 64 through a duct 65. Said chamber 64 has an outlet 66 that aligns with a tube 67. A vent 68 at the top of chamber 64 admits air to prevent siphoning of liquid from the jar 58.

20 A rod 69 having a valve 70 thereon extends through the castings 26 and 2, and has at its lower end an anti-friction roller 69' that rests on the cam wheel 23 to ride the cam and be raised thereby. Said cam causes the valve 70 to temporarily close the passage 71, which leads from the bottom of a pressure and float chamber 72 into the expansion chamber 71' in the casting 26. Near the top of its upward stroke and after the valve 70 is seated, and the 25 cam 23 is moving during the spring retracting portion of its revolution, the valve stem 69 lifts a valve stem 73, having a spring 77 therearound, and unseats a pressure liquid inlet valve 74, thus permitting the pressure fluid to flow from the fitting 75, through the cage 76 and thence into the chamber 72, while the outlet 71 is closed by valve 70.

26 The pressure tank 78 is connected to the fitting 75 by a suitable pipe 79. During the time that the inlet valve 74 is open and the outlet valve 70 is closed, the stem 81 is lifted by means of its float 80 until said float by means of a valve 83 closes a vent 81' in the cover 56. A spider 82 aids in guiding said 30 float stem 81. Said vent 81' communicates with diverging vent holes 84 to allow free escape of gas until the float 80 and the vent valve 83 are lifted.

35 Jam-nuts 85 screwed onto the float stem 81 are adapted to normally rest on cover 56 and to support the float close to the top of the chamber 72.

Within casting 55 is a threaded bore which receives a nipple 86' and which is also adapted to receive the valve seat bushing 87 hav-

ing at its upper end the cage 76 and provided with outlets 87'. The valve stem 73 extends down through the cage 76 and bushing 87, which is provided with a gland 87'' which is shouldered to receive the thrust of the spring 77, which operates between the shoulder of the gland 87'' and the collar 73' fixed to the valve stem 73. Pressure chamber 72 communicates through a port 88, (Figs. 5 and 7), with a cylinder bore 89, that is axially aligned with and is of less diameter than the syrup pump cylinder.

30 A cylinder head 90 at the lower end of the bore 89 prevents the pressure in bore 89 from flowing into the syrup chamber 62 and a piston rod 91 extending through such cylinder head is provided below such head in the syrup chamber 62 with a syrup lifting head 92.

35 The mixing tube or outlet 94 extends from the expansion chamber 71' through a hole 95 in the rear of the casting, and delivers the fluids through the outlet spout 38 into the cup C previously delivered to and resting on the lip 4a.

40 The tube 94 is so steeply aslant that the liquids discharged thereinto will flow out of the spout 38 with sufficient velocity to shoot over into the cup C, but the spout terminates sufficiently behind the front rim of the drip cup to allow any drops which may drip from the end of the spout to drain out through the drain pipe 5' without smearing the lip 4a or the rim 7 of the cup.

45 The pressure liquid outlet valve-lock releasing arm 96, fixed by a pin to the rod 91, is movable up and down by said rod 91 and is adapted to lift the outlet valve releasing rod 97, which is provided with an adjustable stop formed by nuts 97' on said rod 97.

50 Said stop is normally spaced from the arm 96 as indicated in Fig. 5 so that when the power piston 93 is operated by pressure from the chamber 72, the arm 96 will operate with lost motion to lift the rod 97 at the end of a measuring stroke of the syrup pump piston 92.

55 The rod 97 has a collar or tappet 97a which is adapted and arranged to lift the operating arm 98 of the rocking valve lock which is pivoted to the casting 2 by the pin 99 adjacent the valve rod 69. Said rod 69 is provided with a shoulder 100 under which a lock limb 98' of the valve lock may be moved by the spring 101 when the valve rod 69 is elevated by cam 23 to cause the valve 70 to close the outlet 71.

60 When the arm 98 and its lock limb 98' are in locking position, the valve rod 69 and valve 70 are held to positively close the outlet 71; and when the arm 96 lifts the rod 97 and its 65 tappet 97a to the position indicated in Fig. 6a the valve rod 69 is free to be lowered and is so shown in Fig. 5a.

65 The unlocking rod 97 is guided in the cover 56 and the guide 102 which is stationary to the

casting 55, and the spring 101 operates between the guide 102 and a washer 102' resting against the arm 98 and under the spring 101 to normally force the lock into locking position. 103 is a nut on the rod 69 to clamp a bracket 104 onto the set nut 104' on said rod 69. Said bracket is slidable up and down on the rod 97 so that when rod 97 is forced up by pressure on the piston 93 from the chamber 72 the spring 105 on the unlocking rod 97 acts through the bracket 104 after lock 98' is released to force down the valve rod 69, thus to open outlet 71 from the pressure chamber and permit the liquid therein to flow by gravity into the expansion chamber 71'. The roller 69' is thus brought to rest on the cam wheel 23 and the parts remain in the position shown in Fig. 7 until another operation of the crank serves to turn the cam 23 and again lift the roller 69, the valve 70 and valve 74.

The operation of the invention is as follows:

A coin of the required denomination is placed in the slot 12 and runs down into the grooves 12' and seats in the seat 9a of the coin carrier, providing means for connecting the shafts 8 and 15, thus bridging the opening between the limbs of the coin carrier.

The crank 7 is then turned to the right in Fig. 14 and the coin engages the lug 14, (see Figs. 13, 14 and 15), and turns the shaft 15 and gear 17, thereby turning the gear 18, its shaft 19, the gear 21 and its shaft 22, and, acting through the spring 22a (see Figs. 5, 6, and 15), turns the shaft 22' and the cam sheet 23.

The oscillation of the crank 7 is sufficiently ample to turn the crank pin 27' in the direction of the arrows on and adjacent the cam wheel in Figs. 5 and 6, until the crank pin has swung down and passed a vertical, not shown, drawn from the horizontal axis of the cam wheel 23, when the manually tensioned spring 27 operates with a snap action to suddenly complete the revolution of the cam wheel to drive the gear 21 in the direction in which it was turned by the crank, thus completing the revolution of said gear 21 and the train of gears and shafts connected therewith.

The snap action revolution of the gear 21 operates the gear 17, shaft 19, gears 39 and 40, shaft 41, gears 42 and 43 and completes the revolution of the cup delivering wheels 31, so that when the cam 23 comes to rest a cup c has been delivered and hangs suspended by its rim b on the lip 4a.

The beverage delivery mechanism is timed to operate during the portion of the movement of crank 7 which follows the delivery of a cup to the position for being filled. As this mechanism, separately considered is described and claimed in my original application and forms no part of the present application a more detailed description of its action 65 is not here required.

I claim:

1. A cup dispensing machine comprising cooperating rotatable members having peripherally screw threaded portions constructed and arranged to receive and move downwardly cups having edges adapted to engage said screw threaded portions, power transmitting means to actuate said members comprising shafting, a spring arranged first to retard and then accelerate the rotary movement of said shafting, and another spring to cooperate with the first recited spring to accelerate the rotary movement of said shafting after such movement has progressed through the aforementioned retarded portion thereof. 80

2. A cup dispensing machine comprising cooperating rotatable members having peripherally screw threaded portions constructed and arranged to receive and move downwardly cups having edges adapted to engage said screw threaded portions, power transmitting means to actuate said members comprising shafting, a spring arranged first to retard and then accelerate the rotary movement of said shafting, and another spring to cooperate with the first recited spring to accelerate the rotary movement of said shafting after such movement has progressed through the aforementioned retarded portion thereof, said spring which is eccentrically connected with 90 said shafting being in two sections which normally cooperate yieldingly to maintain said shafting at a definite point of rest. 95

3. In a cup dispensing machine, mechanism adapted to move a cup toward a delivery position and then propel it suddenly forward toward a position for receiving liquid, a driven shaft operatively connected with said mechanism, a driving shaft to rotate said driven shaft, a spring section between said shafts, and a snap action spring comprising two upwardly diverging sections which are each anchored at one end and attached at the other end eccentrically to said driven shaft in order to maintain said driven shaft normally at a definite position of rest and adapted, when said driven shaft is rotated to a point beyond dead center to impart to the aforementioned cup delivery mechanism the recited sudden forward movement. 110 115 120

In testimony whereof, I have hereunto set my hand at Salina, Kansas, this 25th day of February, 1931.

FRANK A. MADDEN.
